RECEPTACLE

William F. Bowen, North Attleboro, Mass., assignor to Evans Case Company, North Attleboro, Mass., a corporation of Massachusetts

Application February 18, 1936, Serial No. 64,607

4 Claims. (Cl. 206—41.4)

The invention relates primarily to a receptacle to be carried in the pocket and in the particular form illustrated comprises separate compartments for carrying cigarettes or the like and a lighter of any suitable type although the invention in all its aspects is not confined to such specific uses.

In the accompanying drawing one embodiment of the invention is illustrated. Figure 1 is an end elevation of the device open. Fig. 2 is a fragmentary top plan view of Fig. 1 the lighter being shown in horizontal section. Fig. 3 is a fragmentary vertical section on the line 3—3 of Fig. 2. Fig. 4 is a fragmentary vertical section on the line 4—4 of Fig. 2 and Fig. 5 is a fragmentary vertical section on the line 5—5 of Fig. 2 when the receptacle is closed.

The receptacle comprises a member 10 to which a complementary member 11 is hinged along one side at 12. A catch 13 on the member 10 engages a locking member 14 on the member 11 when the receptacle is closed. At one end of the member 11 is a section 15 in which are shown cigarettes 16 which may be held in place by a band 17 which may be resiliently mounted as well known in the art. In the member 11 facing the section 15 is a section 18 in which are illustrated cigarettes 19 held in place by a band 20 which may be resiliently mounted in any suitable manner well known in the art.

While cigarettes have been illustrated in the sections 15 and 18 it will be understood that the invention is not confined to these, but the sections may be employed for any other suitable purpose.

Beyond the section 16 in the member 10 is a section 21 and mounted at the end of the section 21 toward the hinge 12 is a carrier 22. The carrier 22 consists of a bottom member 23 and three side members 24. The fourth side of the carrier, preferably toward the hinge 12, is open and unobstructed. The carrier 22 toward the edge away from the hinge 12 is mounted on a hinge 25 in the bottom of the section 21 and a spring 26 normally holds the carrier 22 in the erect position indicated in Figs. 1, 2, 3, and 4. A lighter 27 of any suitable construction may be mounted in the carrier 22. The lighter 27 may be inserted through the open side of the carrier 22 and may be held in position in the carrier in any suitable manner. In Fig. 4 the sides of the carrier 22 are indicated as bent at 28. The sides may be made of resilient metal and so form a tight spring or friction hold upon the lighter 27. It should be understood of course that the lighter 27 should

not be wider than the section 21 and should be somewhat shorter than the section 21. It also should not be thicker than the depth of the receptacle when closed. The member 11 is provided with a section 29 opposite the section 21 and of approximately the same size.

This construction makes it possible to hold the lighter in position for convenient use while it may be readily removed for filling, repairs or replacement.

When the receptacle is opened in the position of Fig. 1 the spring 26 will hold the carrier 22 in the position indicated in the Fig. 3 in which position the lighter 27 will be held erect as indicated in Fig. 1. The operating and lighting mechanism at the top 30 of the lighter 27 is thus readily accessible and available for operation and use. When the receptacle is closed the section 29 engages the lighter 27 and forces it and the carrier 22 to the recumbent position indicated in Fig. 5 and it may be held in this position by the catch 13 engaging the locking member 14. The lighter may be forced down by hand and then the device may be closed and locked.

Inasmuch as fumes of the igniter of the lighter or of the fluid in it may have a bad effect on the contents of the sections 15 and 18 it is desirable to provide a gas and liquid tight partition or wall between the sections 21 and 29 and the sections 15 and 18. In the device illustrated this is accomplished by providing at the end of the section 15 a partition consisting of two walls 31 rising to approximately the upper edge of the wall of the member 10. Between these walls 31 is placed a suitable packing 32 which may be sulphur-free rubber or felt or other like materials. This gasket 32 may be of any suitable form and may be fastened in by glue or in any other suitable manner. Opposite the walls 31 in the member 11 is provided a partition consisting of a single wall 33 which protrudes beyond the top of the side walls of the member 11 so that when the receptacle is in the closed position indicated in Fig. 5 the wall 33 enters between the walls 31 and engages the gasket 32 to form a tight seal.

One of the sections 15 or 18 may be omitted and when the lighter is thin enough to lie wholly in the section 21 the section 29 may be omitted and only a sealing device such as 33 may be needed on the member 11.

The invention is not confined to the particular embodiment illustrated but may be carried out in other forms.

I claim as my invention:

1. In a receptacle, two members, a hinge connecting them together, a carrier for a lighter on one member having an open side, the carrier having resilient sides for clasping and holding a lighter, a spring hinge mounting the carrier at the side away from the first mentioned hinge and holding the open side of the carrier toward the first mentioned hinge so that the lighter is normally erect, so constructed and arranged that when the other member is swung on its hinge it engages the lighter to turn the carrier on its hinge to a prostrate position of the lighter, and means for fastening the members in this position.
2. In a receptacle, two members, a hinge connecting them together, a carrier for a lighter on one member having an open side, a spring hinge mounting the carrier at the side away from the first mentioned hinge and holding the open side of the carrier toward the first mentioned hinge so that the lighter is normally erect, so constructed and arranged that when the other member is swung on its hinge it engages the lighter to turn the carrier on its hinge to a prostrate position of the lighter, and means for fastening the members in this position.

3. In a receptacle, two members, a hinge connecting them together, a carrier for holding a removable lighter on one member, a removable lighter in the carrier extending beyond the side walls of the carrier, a spring hinge mounting the carrier at the side away from the first mentioned hinge so that the lighter is normally erect, so constructed and arranged that when the other member is swung on its hinge it engages the lighter to turn the carrier on its hinge to a prostrate position of the lighter, and means for fastening the members in this position. 5

4. A receptacle having compartments for such articles as cigarettes and including a compartment for a lighter, two members, a hinge connecting them together, a carrier for holding a removable lighter on one member, a spring hinge mounting the carrier at the side away from the first mentioned hinge so that the lighter is normally erect, so constructed and arranged that when the other member is swung on its hinge it engages the lighter to turn the carrier on its hinge to a prostrate position of the lighter and a liquid and fume impervious partition wall for the compartment containing the lighter. 10 15 20 25

WILLIAM F. BOWEN.
